UNITED STATES PATENT OFFICE.

HOWARD L. WADSWORTH, OF CLEVELAND, OHIO, ASSIGNOR TO SAND MIXING MACHINE COMPANY, INCORPORATED, OF NEW YORK, N. Y., A CORPORATION OF OHIO.

SAND CUTTING AND SCREENING MECHANISM.

1,332,939.

Specification of Letters Patent.

Patented Mar. 9, 1920.

Application filed April 12, 1917. Serial No. 161,386.

To all whom it may concern:

Be it known that I, HOWARD L. WADSWORTH, a citizen of the United States, and a resident of Cleveland, county of Cuyahoga, 5 and State of Ohio, have invented a new and useful Improvement in Sand Cutting and Screening Mechanism, of which the following is a specification, the principle of the invention being herein explained and the 10 best mode in which I have contemplated applying that principle so as to distinguish it from other inventions.

The present improvements, relating as indicated to a device for cutting and screening sand, have more particular regard to a machine designed to be used in foundries for cutting molding sand after it comes from the molds and at the same time for screening the sand to remove therefrom the 15 various sprues and other articles which are always left in this sand. The machine is further adapted to be automatically operated when moved over a sand pile. To the accomplishment of the foregoing and related ends, said invention, then, consists of the means hereinafter fully described and particularly pointed out in the claims.

The annexed drawing and the following description set forth in detail certain 20 mechanism embodying the invention, such disclosed means constituting, however, but one of various mechanical forms in which the principle of the invention may be used.

In said annexed drawings:—

35 Figure 1 is a side elevation of my improved machine, showing the same in operation upon a sand pile; Fig. 2 is an end elevation of the same from the front; Fig. 3 is a plan view of the machine; and Fig. 40 4 is a section on the line 4—4, Fig. 1.

Several machines have been designed and are in use for renovating or cutting used molding sand, such machines being of two general types. The machines of one type 45 are designed to operate upon a substantially round and large pile of sand. The machines of the second type are designed to operate upon a long and relatively narrow pile of sand and they so operate by lifting all of 50 this sand to a considerable height and then passing the same through a screening plant. The present machine may be said to be of the second type, but it is designed to cut and screen the sand as the machine is moving 55 along over a long narrow sand pile, the

screening being effected without the necessity of raising the sand to any great height and without requiring any complicated or expensive machinery for this purpose.

The general construction of the machine 60 is best seen in Fig. 1, the machine consisting of a vehicle or framework which is movable over the ground and which consists of side and end members 1 and 2 respectively connected together to form a 65 rectangular framework, upon which are mounted vertical members 3, which are in turn connected together by other side and end members, thus forming an open box-like framework of considerable strength. 70 This frame is mounted upon suitable wheels 4, these wheels bearing sprockets 5, which are driven by means of chains 51 operated from a sprocket 15 on a shaft 7 on which there is mounted a suitable source of power, 75 such, for example, as an electric motor 8. Adjacent to this motor 8 is a platform 9 supported by the upper members of the frame upon which the operator may stand and control the operation of the vehicle. 80

The controlling devices, such as the switches for the motors, if one is used, and the clutches (to be described presently), are grouped convenient to this platform, but it is not considered necessary to show such 85 elements or their mounting in detail, and in themselves they form no part of the present invention.

Mounted at the forward end of the frame is an inclined surface formed by a hinged 90 scoop 10, provided with small supporting rollers 50 at its forward end and adapted to rest upon the floor over which the vehicle is to move. The scoop is hinged about an axis 12 and is thus adapted to be swung up 95 when not in use. Mounted above and adjacent to the upper end of the inclined surface 10 is a cutter consisting of a plurality of curved blades 13 mounted to form a cylinder, this cylinder being rotatably supported in the frame and being driven by means of chains 14 operated over sprockets 15 on the shaft 7 and other sprockets 16 on the cylinder. The function of this cutter is to cut or mix sand which is elevated by 100 means of the inclined surface 10 and to throw the same rearwardly. In order to more thoroughly break up any lumps in the sand which may be missed by the cutter, and to remove articles which may collect 105 110

therein, I provide a reciprocating screen 20 mounted between the side members of the frame and about on the level of the top of the incline 10. This screen is supported 5 and operated by means of pivoted arms 21, which are driven forward and backward by means of arms 22. The arms 21 are connected by a bar 22 with an upwardly extending portion having a slot 23 therein in 10 which operates a crank-pin 55 mounted on a sprocket 25. The latter is carried on a short shaft in the form of a pin 24 set in a downwardly extending lug 56 attached to the side bar 1. The sprocket is operated by 15 a chain 26 driven from a sprocket 57 on the shaft 7, and it will be understood that either one or more sprockets may be used to operate the screen, although I have here shown two such driving means. A shaking motion is 20 thus given to the screen and the sand which is deposited thereon is very finely broken up and is sifted down on to the floor between the wheels of the vehicle and forms a sand pile 28 as indicated in Fig. 1.

25 Between the screen 20 and the cutting cylinder 12 is a box 29 mounted below the level of the screen and adapted to receive articles such as pouring sprues, clamps and other small articles, which unavoidably get into 30 the molding sand. These same articles, having considerable weight, are not usually thrown onto the screen by rotation of the cutting cylinder, but fall, as soon as they leave this cylinder, into this box 26 from 35 which they may be removed at intervals.

The form of the inclined surface is indicated in Fig. 3, the surface of this scoop being preferably narrowed at its upper end so that it lies between the ends of the cutting 40 cylinder 13, thus insuring that all of the sand raised by this scoop is operated on by the cylinder. For the same reason the screen 20 is made wider than the cutting cylinder in order that it will receive all of the sand 45 thrown backward from this cylinder, even though the sand is directed slightly toward one side or the other, and thus all of the sand which passes through the machine is both cut by the blades of the cylinder and 50 sifted by the shaking action of the screen. The sides and end of the screen are extended upward to prevent the falling of material.

The operation of the machine is controlled 55 from the operator's platform 9 by means of clutches 30 which control the connection of the sprockets 8 with the shaft 7 so that the machine may be either moved over the floor and the cutting cylinder operating simultaneously so that the forward movement of 60 the machine may be stopped for the purpose of handing an unusual amount of sand which may be before the cutting cylinder. For convenience both clutches are connected by arms 31 extending to, and operated by a 65 pivoted handle 32. In this way the machine

is adapted to handle without difficulty any inequalities in the sand pile which would otherwise cause the machine to choke up, or to pass the sand therethrough after properly mixing and screening it.

70 Other modes of applying the principle of my invention may be employed instead of the one explained, change being made as regards the mechanism herein disclosed, provided the means stated by any of the 75 following claims or the equivalent of such stated means be employed.

I therefore particularly point out and distinctly claim as my invention.

1. In a machine of the character described, 80 the combination of a vehicle movable over the floor, an inclined sand feeding scoop mounted on said vehicle with one end resting upon the floor, a rotatable mixing cylinder mounted in said vehicle, and adapted to receive and agitate sand from the top of said scoop, and a horizontal screen mounted in said vehicle to the rear of said cylinder and adapted to catch the sand distributed from said cylinder, whereby all the sand is 85 cut and screened in a horizontal plane above the floor.

2. In a machine of the character described, 90 the combination of a vehicle movable over the floor, an inclined sand feeding scoop 95 mounted on said vehicle with one end resting upon the floor, a rotatable mixing cylinder mounted in said vehicle, and adapted to receive and agitate sand from the top of said scoop, and a receptacle mounted in said vehicle between said cylinder and said screen, and adapted to collect extraneous material from such sand.

3. In a machine of the character described, 105 the combination of a vehicle movable over the floor and provided with wheels and a raised frame, an inclined sand feeding scoop mounted on said vehicle with one end resting on the floor, a rotatable mixing cylinder mounted in said frame and adapted to receive and agitate sand from the top of said scoop, and a horizontal screen carried by 110 said frame to the rear of said cylinder and adapted to catch the sand distributed in a horizontal plane above the floor.

4. In a machine of the character described, 120 the combination of a vehicle movable over the floor and provided with wheels and a raised frame, an inclined sand feeding scoop mounted on said vehicle with one end resting on the floor, a rotatable mixing cylinder mounted in said frame and adapted to receive and agitate sand from the top of said scoop, and a receptacle mounted in said vehicle between said screen and said cylinder 125 and adapted to collect extraneous articles in such sand.

Signed by me, this 23rd day of March 1917.

HOWARD L. WADSWORTH.
